UNITED STATES PATENT OFFICE.

D MC RA LIVINGSTON, OF NEW YORK, N. Y.

DESIGN FOR AN AUTOMOBILE-HOOD.

47,854.

Specification for Design.

Patented Sept. 21, 1915.

Application filed December 21, 1914. Serial No. 878,444. Term of patent 7 years.

To all whom it may concern:

Be it known that I, D MC RA LIVINGSTON, a citizen of the United States, and a resident of the city of New York, borough of Manhattan, in the county and State of New York, United States of America, have invented a new, original, and ornamental Design for an Automobile-Hood, of which the following is a specification, reference being had to the accompanying drawing, forming part thereof.

Figure 1 is a perspective view of an automobile hood embodying my new design;

Fig. 2 is a side view thereof particularly illustrating the configuration of the left segment of the hood; Fig. 3 is a plan view of said automobile hood showing the configuration of both segments of the hood.

I claim:

The ornamental design for an automobile hood, as shown.

D MC RA LIVINGSTON.
